FOLDING LEG CONSTRUCTION AND LOCKING MEANS THEREFOR

John Kearsley Mitchell, Bryn Mawr, Pa.

Application May 28, 1934, Serial No. 727,871

6 Claims. (Cl. 311—82)

This invention relates to improvements in folding table leg constructions for bridge tables and other like pieces of furniture, and more particularly to improved automatic locking and releasing mechanism for folding table legs.

In my copending application Ser. No. 671,609 dated May 18, 1933, for Game table, I have disclosed improvements in bridge table constructions, including novel composite cover members 10 and improved hinges.

I have now discovered that the utility of these improved leg constructions may be appreciably increased by providing positive retaining means for retaining the folding legs in locked position 15 when folded under the tables in combination with added spring means for positively urging the legs into their vertical, operative positions in the respective leg sockets.

The novel improvements of the present invention permit a positive locking of the legs in folded position, together with a definitely controlled automatic opening of the legs when desired.

Features of the present invention will be described more in detail hereinafter, and with particular reference to the accompanying drawings forming a part hereof, in which the several parts are designated throughout the several views by like numerals, and in which

Fig. 1 is a fragmentary top plan view, partly in broken section, of the top of a table showing the location of the table leg mechanism;

Fig. 2 is an elevation of the leg member in locked operating position;

Fig. 3 is a view similar to Fig. 2 showing the leg in a locked operating or folded position;

Fig. 4 is a vertical section taken on line 4—4 of Fig. 2;

Fig. 5 is a vertical section taken on line 5—5 of Fig. 1;

Fig. 6 is a bottom plan view of the table shown in Fig. 1, showing the details of the locking and automatic releasing mechanism;

Fig. 7 is a vertical section taken on line 7—7 of Fig. 2;

Fig. 8 is a vertical detail through the table leg releasing mechanism taken on line 8—8 of Fig. 12;

Figs. 9 and 10 are views similar to Figs. 2 and 3 showing the leg locking mechanism added thereto;

Fig. 11 is a vertical section taken on line 11—11 of Fig. 10;

Fig. 12 is a view of table leg locking and releasing mechanism taken on line 12—12 of Fig. 6;

Fig. 13 is a detail of the table leg locking and

releasing control mechanism taken at right angles to the showing in Fig. 12; and

Fig. 14 is a detail of modified form of table leg locking means.

Considering the invention in more detail, and with particular reference to the drawings, the novel automatic locking leg constructions are shown in combination with a table designated generally by the numeral 100, having a table top 101 mounted on a frame comprising side panel members 102 and central panel top member 103. These table members may be secured together in any desired manner, and the top of 101 instead of being unitary, as shown, may comprise composite tops of the types shown in my 15 applications Ser. No. 671,609 filed May 18, 1933, and Ser. No. 727,870 filed May 28, 1934.

Hinge constructions 200 are severally located at the corners of the table and secured to and under the frame or side wall members 102. The 20 leg members 300 are mounted in the hinge constructions 200 in a manner to be described more in detail hereinafter. Hinge constructions, as noted hereinabove, conform generally to the constructions disclosed and claimed in my application Ser. No. 727,870 filed May 28, 1934. The essential features of such constructions comprise 25 an angular bracket member 210, having depending walls 211 usually terminating in side flanges 212, the walls and flanges being adapted to abut 30 against the table frame 102 and be secured thereto by screws or the like, suitable apertures 213 being formed in the wall and flange portions of the bracket members. A socket member 250 formed of spaced cam plates 251 having an integral backing 252, if desired, and a bridging member 253, may be secured to the bracket member 210 in any desired manner. The cam plates 250 may be provided with extensions 254 extending through and above the base plate 210 40 of the bracket member, and giving a deep seat for the ferrule 310 or the table leg member 300. The bridging member 253 may be canted forward to permit the withdrawal of the leg 300 from the socket 250 and its rotation thereabout to the 45 folded position, indicated in Fig. 3. The cam plates are provided with interior and exterior cam surfaces 260 and 261, respectively. The interior cam surface is so shaped and arranged as to seat a guide pin 311 of the table leg, and a 50 spring retaining pin 312 adapted to serve as a support for the spring 313, which may be secured to a corner 214 of the angle bracket member 210. The cam surfaces 260 are so configured and arranged as to permit the legs 300 to 55

be withdrawn downwardly and then forwardly at right angles to its original position and nested in place and folded up under the table apron; all as disclosed and claimed in my copending 5 application Ser. No. 671,609 above referred to.

The cam surfacings 250 are further provided with forward extensions or lugs 255, and preferably integral therewith. These lugs are adapted to receive torsion pin spring members 270 and 10 stop members 271. A torsion spring 275 may be wound on the member 270 and anchored on the pin and on a dog or arm 280 in engagement with the leg 300, and so constituted and arranged so as to maintain the latter under pressure at all 15 times. The torsion spring 275 may be wound to a desired tension by means of a pawl or ratchet member 272, the desired tension being maintained by contacting the pawl 272 with the stop pin or dog 271.

20 It will be seen that member 280, being under constant tension, urges the leg 300 to the vertical locked position nested or seated in the straight or tapered wall socket 250 at all times.

When it is desired to fold up the legs, they may 25 be locked in position against the tension of the spring-urged lever 280 in a manner now to be described. The legs 300 may be provided with stops 400 formed with an angular plate 401 and secured to the leg members at the top thereof, 30 and preferably at the ferrule portion 310 as by suitable screws 402. The plates 401 may also be secured to ferrules and made integral therewith as by means of welding, brazing, soldering, or riveting. These stops 400 are adapted to hold 35 a bottom 320 of a leg member when a leg is folded up under the table and an adjacent leg is likewise folded up so as to bring the finger or retaining member 400 under the end of the leg of the preceding, now folded, leg member, as shown 40 in detail in Figs. 6 and 11. It will normally be sufficient to provide only three of the foldable table legs with stop members 400 attached to the legs at the upper ends or ferrules thereof. It will, of course, be appreciated that the spacing 45 or location of the stop member 400 may be varied appreciably without departing from the spirit of the present disclosures, or of the scope of the appended claims.

The fourth leg may be provided with a separate 50 rate locking and release mechanism, designated generally by the numeral 500, as shown more particularly in Fig. 6, the details being shown in Figs. 12 and 13. The locking and release mechanism now referred to comprises a rocking arm 55 or lever 510 rotatably mounted on a pin 511 adapted to be screwed into the table frame. An escutcheon plate 512 serves as a support and means for retaining the rocker arm in place, and is itself held in place by screws 513 or equivalent securing members. The rocker arm is provided with an angular extension 514 at one end thereof forming a support for an abutted and superimposed leg 300. The support 514 may have a felt or leather pad 515 secured thereto to prevent 60 rubbing or marring of the table leg. The rocker arm is maintained in normal or locked position by any suitable means, such as a leaf spring 516, secured to the escutcheon plate by machine screw 517. While a leaf spring has been shown and 65 described, it will, of course, be appreciated that a spiral spring or a rubber block may be used to give the desired results. The spring-urged rocker arm 510 may be withdrawn from its normal operative locking position to permit release of the legs 70 300 by the spring-urged arms 280. This release

is effected by rotating the rocker arm about its pivot 511 by means of a push button 518 secured to the rocker arm in any suitable manner, as by means of a pin 519, thus when the legs are folded up under the table the button 518 will be pushed permitting the legs 300 to pass by the rocker arm. When the button 518 is released, the rocker arm will be snapped into position and the stop portion 514 will be brought under and in locking engagement with the adjacent table leg. In this manner the set of four legs will be held in folded locked position through the members 514 and the leg supporting members 400.

Referring now to Fig. 14, a modified form of leg locking device is shown comprising a socket member 330 formed in or secured to the bottom of the table leg 320 and adapted to engage a ball 331 formed on one leg of a U-spring member 332, which member is itself secured to a ferrule 310 of a leg member 300. This construction permits the several legs to snap in place and be held mutually locked against the tension of springs 275 without requiring a separate locking mechanism 500, as previously described. In the latter modified construction, when one leg is released it will readily be seen that all the legs will be consecutively released without requiring manual operation.

It will now be appreciated that there has been provided an automatic leg locking and releasing mechanism for table leg constructions, and more particularly for such constructions in which the legs are adapted to nest in socketed hinge members when in use, and are adapted to be folded up under a table frame when not in use. Further, the novel improvements of the present invention includes means for positively urging the legs into operative position when the leg locking or releasing mechanism is released.

While certain novel features of the invention 40 have been disclosed and are pointed out in the annexed claims, it will be understood that various omissions, substitutions and changes may be made by those skilled in the art without departing from the spirit of the invention.

What is claimed is:

1. In bridge tables or other like constructions having spring tensioned folding legs normally urged in operative position and adapted to be nested under the table frame when not in use and to be positively locked in socketed hinge members when in the operative position, the improvements comprising stop members formed on the legs and adjacent the hinge portions thereof, said stop members being adapted to engage the tips of abutted and folded legs and hold same in folded position whereby to mutually engage and lock each other, and separate locking means for releasably holding the mutually engaged and locked legs in inoperative, folded position.

2. A construction as described in claim 1, including a locking member for at least one of the table legs comprising a spring-urged rocking arm and means for releasing said locking arm.

3. In the table described in claim 1, said separate locking means comprising a rocker arm having an angular surface adapted for supporting and retaining a table leg, means for maintaining the arm in operative position, and other means formed on the arm for moving the same out of operative position.

4. A bridge table construction having a train of perimetrical folding legs separately foldable inwardly of the table top when in inoperative

position to nest under the said top, and comprising socketed hinge members having cam plates, guide pins and floating pivots in the leg members adapted to engage cam surfaces in the socket members whereby the legs may be moved into erected and out of folded position, and a plurality of spring-urged means mounted on the hinge members for automatically moving the separate legs in a train from their folded into erected operating position in their respective sockets.

5 5

10 10

15 15

5. In an improved bridge table construction having folding legs, and comprising socketed hinge members having cam plates, guide pins and floating pivots in the leg members adapted to engage cam surfaces in the socket members whereby the legs may be moved into and out of nested operative position, the improvements com-

prising a plurality of spring-urged means mounted on the hinge members for automatically moving the separate legs into normal operating position in their respective sockets, at least one of said means comprising a spring-urged arm in engagement with the leg and below the pivot thereof.

6. A locking mechanism for folding table legs, comprising separate spring-urged means for separately moving the legs into operative position, means on the legs for releasably engaging and holding each other in a mutually interlocked train, and separate spring locked means on at least one of the leg members for retaining the train of leg members in folded, inoperative position.
